Inventor
Michael Paridon
by his Attorney

John F. Nolan

UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

MATCH MACHINE.

Application filed June 12, 1923. Serial No. 644,839.

To all whom it may concern:

Be it known that I, MICHAEL PARIDON, a citizen of the United States, and resident of Barberton, in the county of Summit and State of Ohio, have invented certain new and useful Improvements in Match Machines, of which the following is a specification.

This invention relates to match machines employing endless carrier chains for the match splints, having reference especially to mechanism whereby the carrier chain is automatically raised and lowered in the region of the composition-applying station during the stopping and the starting, respectively, of the match machine, in order to obviate all liability at such times of dragging the splints upon and over the composition applying devices. Mechanism for the purpose mentioned is set out in Letters Patent of the United States No. 1,165,536, dated December 28, 1915, by reference to which it will be seen that the composition devices of the match machine therein illustrated include a composition-applying roller which is operatively connected with the chain actuating mechanism and also with an electric motor in such a manner as to be operative by either instrumentality as desired, and that a fluid-actuated hoisting mechanism operative to raise or lower the portion of the chain above the roller, is provided, together with means whereby the motor and the chain actuating mechanism may be rendered active and idle at predetermined intervals in respect to the chain raising and lowering operations.

The object of the present invention is to simplify the previous apparatus by dispensing with the fluid actuated hoisting mechanism, and providing, in lieu thereof, devices under the influence and control of the electric motor for accomplishing the timely raising and lowering of the carrier chain, all of which will be hereinafter described and claimed.

In the drawings—

Figure 1 is a side elevation of a composition applying structure and associated mechanisms of a match machine embodying a preferred form of my invention, only so much of the machine being shown as is necessary to illustrate the invention. In this view the portion of the chain crossing the composition roller is shown in down position

with its splints depending into the "dipping" path.

Fig. 2 is an end elevation of the drive connection and clutch therefor between the electric motor and the shaft for operating the chain raising and lowering mechanism, showing the clutch in idle position.

Fig. 3 is a similar view, showing the clutch in active position.

Fig. 4 is an end elevation of the apparatus adjacent the motor.

Referring to the drawings, 10 designates a part of the endless splint-carrying chain of a continuous match machine, and 11 a pair of power-driven gear wheels mounted on a transverse shaft 12 and meshing with the gear racks 13 of the chain in a manner to actuate the latter, as usual.

14 designates a composition vat supported by a suitable frame 15, and 16 designates a composition-applying roller mounted to rotate partly within the vat and beneath the working route of the chain so that the free ends of the splints depending from the chain progress through the composition on the periphery of the roller and thus are "dipped". A mixer 17 is mounted to rotate within the lower portion of the vat directly under the composition roller; the shafts 18, 19 of said mixer and roller, respectively, being journaled in suitable bearings in the end walls of the vat, and being coupled to the hubs of intermeshing gear wheels 20, 21 respectively. Loose on the shaft 18 are two spaced sprocket wheels 22, 23 flanking a wide faced ratchet wheel 24 fast on the shaft. The wheels 22, 23 are provided on their inner faces with pawls 25, 26, respectively, which engage the teeth of the ratchet wheel, whereby when either wheel 22 or 23 is rotated the shaft 18 is actuated thereby. The sprocket wheel 22 is connected with and driven from a sprocket wheel 27 on one end of the shaft 12 by means of a chain 28; the mixer and roller thus being driven at a normal speed during the progression of the match chain.

The sprocket wheel 23 is connected by means of a chain 29 with a sprocket wheel 30 on a suitably mounted shaft 31 which is geared to the shaft 32 of an electric motor 33, which, being in operation when the match machine is idle, effects through the transmission gearing the rotation of the ratchet wheel 24 and its shaft 18 with a

relatively slow movement with corresponding motion of the mixer and roller.

The splint chain is supported and guided in its travel across the composition-applying roller by parallel bridge bars 34 carried by a supporting frame 35 which is hinged at one end on the shaft 12. The opposite end of this frame carries a hexagonal drum 36 about which the splint chain 10 is flexed in its travel. On the sides of the frame are laterally-projecting anti-friction rollers 37 against which bear sector cams 38 carried by a rock shaft 39 having its bearings in boxes on the frame 15 for the composition vat, whereby when the shaft 39 is properly actuated the hinged frame 35 and bars 34, with the portion of the splint chain thereon, may be raised or lowered to move the splints from or into the path of the composition roller, as desired. Fast on the rock-shaft 39 is a lever 40 which is connected by means of a link 41 with the usual clutch devices of the main drive mechanism of the match machine, whereby when the rock-shaft is moved in one direction to lower the splint chain, such devices are actuated to start the match machine, and when the rock-shaft is moved in the opposite direction to raise the splint chain 20 such devices are shifted to stop the match machine.

The foregoing described mechanism, excepting as hereinafter described, is similar in construction and operation to mechanism 35 illustrated in Patent No. 1,165,536 aforesaid.

In pursuance of my present invention I dispense with the fluid-actuated hoisting mechanism and the associated gearing and contact making and breaking devices shown and described in said patent for the purpose of raising and lowering the splint carrier, and also of effecting the stopping and the starting of the match machine, and, instead, provide mechanism of the following preferred construction and operation: Mounted in suitable bearings located above and laterally of the composition mechanism, is a shaft 42 which extends longitudinally of the machine, and is provided adjacent the motor with a loose pulley 43 which is connected by means of a belt 44 with a smaller pulley 45 fast on the shaft 32 of the electric motor; a suitable clutch 55 being provided whereby the pulley can be temporarily locked on the shaft when the motor is energized. This clutch, in the form shown, comprises a sector 46 which is keyed on the shaft, laterally of the pulley, and which sector has a peripheral flange 47 located normally adjacent the rim of the pulley and in the space between the runs of the belt 44. (See Fig. 2). Depending from the sector 46 is an arm 48 which is held normally in contact with a trip mem-

ber by means of a retracting spring 49 which is secured to the sector and to a fixed stud 50, the peripheral flange 47 of the sector in that case occupying the position mentioned between the runs of the belt. The trip member comprises one arm 51 of a lever which is fulcrumed on a suitably-disposed stud 52, such arm being held normally in the path of the sector arm by means of a torsion spring 53 on the stud. Depending from the other arm of the lever is a hand rod 54. The relation of the parts just described is such that if, during the operation of the motor, the hand rod be raised the lever will be swung to depress the trip arm 51 below the sector arm 48 and the spring 49 will pull the sector in a manner to draw its flange 47 between the opposing run of the traveling belt 44 and the rim of the pulley, whereupon the contiguous portion of the belt will forcibly grip the flange and positively rotate the sector and its shaft 42. (See Fig. 3). If the hand rod be released to permit the trip arm to resume its normal position, immediately after the escape of the sector arm, the latter arm will, upon a complete rotation of the sector and shaft, again abut against the trip arm and be held thereby with the sector flange in idle position in readiness for a succeeding operation.

Fast on the shaft 42 is a bevel gear 55 which meshes with a similar gear 56 on a short shaft 57 having its bearings in brackets 58 on the main frame structure. On one end of this shaft is a crank arm 59 which is connected by means of a link 60 with an arm 61 fast on the rock-shaft 39 carrying the sector cams 38, the relation of the parts being such that the chain is in down or active position when the shaft 42 is at rest. At this juncture the match machine is in operation, and the motor 33 is idle. To stop the machine the motor is energized, and the trip arm 51 is moved to free the sector arm, whereupon the sector and its shaft make one complete rotation and stop. The ratio of the bevel gearing is such that in the rotation of the shaft 42, the shaft 57 makes one half rotation, thus partially turning the rock-shaft 39 and its sector cams 38 in a manner to raise the frame 35 and bars 34, and the part of the carrier supported thereon. The movement of the rock-shaft lever 40 also pulls the link 41 and releases the clutch devices of the main drive mechanism of the match machine, thereby stopping the latter. While the match machine is idle the motor continues in operation, and through its gear connections with the sprocket wheel 23 slowly rotates the mixer and the composition roller; it being noted that, in the present instance, the reducing gearing between the motor and the shaft 31 comprises a worm 62 in mesh with a

worm wheel 63 included in the gear train, the shaft 64 of said worm being connected with the motor shaft by bevel gears 65.

- Preparatory to starting the match machine the operator manipulates the hand rod 54 to permit the rotation of the shaft 42 by the motor, as before described in respect to the operation of stopping the machine. During the rotation of the shaft 42 the shaft 57 is partially rotated in a manner to lower the crank and link connections, thus swinging the sector cams 38 in proper direction to the framework 35, 34 and the carrier thereon. At the same time the lever 40 is properly swung by the motion of the rock-shaft 39 to push the link 41 and lock the clutch devices of the match machine, thus starting the latter. This done the current is switched from the motor until the next succeeding stopping operation, and so on.

There is preferably provided an additional pair of sector cams 38' to facilitate the operation of raising and lowering the carrier supporting frame. These cams are borne by a rock-shaft 39' having its bearings at the side of the vat frame opposite to the rock-shaft for the other pair of cams. The rock-shaft 39' is provided with an arm 61' which is connected by means of a link 60' with a crank arm 59' on a short cross-shaft 57' adjacent the longitudinal shaft 42. On the two shafts are fixed two intermeshing bevel gear wheels 55', 56' similar to the wheels 55, 56, and hence during the rotation of the shaft 42 the two sets of wheels and the crank and link connections with the respective rock shafts are concurrently actuated.

It is to be understood that my invention is not limited to the specific form or forms of mechanism herein disclosed, as the same may be modified within the principle of my invention and the scope of the appended claims.

45 I claim—

1. In a match machine, the combination of a splint carrier, a composition applying element below the path of the carrier, mechanism for actuating said element during the 50 operation of the carrier, a motor, operative connection between the motor and the said element, a vertically-movable carrier support, means for raising and lowering said support, transmission means between the motor and said raising and lowering means, and means whereby said transmission means can be rendered active and idle at intervals.

2. In a match machine, the combination of a splint carrier, a composition applying 60 element below the path of the carrier, mechanism for actuating said element during the operation of the carrier, an electric motor, operative connection between the motor and said element, a vertically-movable carrier support, means for raising and lowering said

support, normally inactive transmission means between the motor and said raising and lowering means, a clutch device manually operative to render said transmission means active, and automatically operative, 70 when released, to determine the period in action of the transmission means.

3. In a match machine, the combination of a splint carrier, a composition applying element below the path of the carrier, mechanism for actuating said element during the 75 operation of the carrier, an electric motor, operative connection between the motor and said element, a vertically-movable carrier support, means for raising and lowering 80 said support, transmission means between the motor and said raising and lowering means, means whereby said transmission means can be rendered idle and active at 85 predetermined intervals, and means actuated by said raising and lowering for determining the operation of the carrier.

4. In a match machine, the combination with the movable carrier support and its 90 raising and lowering cam element, of a shaft, a crank thereon, connections between said crank and the cam element, a second shaft, gearing between the two shafts, a normally loose pulley on said second shaft, an electric motor, transmission means between said 95 motor and the pulley, and means for locking said pulley to the shaft.

5. In a match machine, the combination with the movable carrier support and its 100 raising and lowering cam element, of a shaft, a crank thereon, connections between said crank and the cam element, a second shaft, gearing between the two shafts, a normally loose pulley on said second shaft, an electric 105 motor, transmission means, including a belt, between said motor and the pulley, a clutch device, a spring acting to force said device between the belt and the pulley, and a manually operative trip element normally located to maintain the clutch device in idle 110 position against the action of the spring.

6. In a match machine, the combination with the movable carrier support and its 115 raising and lowering cam element, of a shaft, a crank thereon, connections between said crank and the cam element, a second shaft, gearing between the two shafts, a normally loose pulley on said second shaft, an electric 120 motor, transmission means, including a belt, between said motor and the pulley, a clutch device including a sector fast on said second shaft and having a peripheral flange adjacent the rim of the pulley and also a stop portion, a spring acting to position said sector with its flange between the belt and the pulley and a manually operative trip element 125 normally located in the path of said stop portion so as to position the clutch device with its flange free from the belt.

7. In a match machine, the combination of 130

a splint carrier, a composition applying element below the path of the carrier, mechanism for actuating said element during the operation of the carrier, an electric motor, operative connection between the motor and said element, a vertically-movable carrier support, a cam element operative to raise and lower said support, a shaft, a crank thereon, connections between said crank and the cam

element, a second shaft, gearing between the two shafts, a normally loose pulley on said second shaft, transmission means between said motor and the pulley, and means for locking said pulley to its shaft.

Signed at Barberton, in the county of ¹⁵ Summit and State of Ohio, this 7th day of June, A. D. 1923.

MICHAEL PARIDON.
